ATTACHMENT FOR INTERNAL COMBUSTION ENGINES

Urban Sauer, Pittsburgh, Pa., assignor of one-third to Harry R. Levy, McKeesport, Pa.

Original application July 6, 1938, Serial No. 217,764. Divided and this application August 24, 1938, Serial No. 226,593

1 Claim. (Cl. 230—95)

This invention relates to internal combustion engines, and more particularly to an attachment to be placed on the exhaust side of the engine.

An object of this invention is to provide an attachment of this kind which is adapted to form a suction in the exhaust line so as to facilitate the scavenging of the burned gases from a combustion chamber of the engine.

Another object of this invention is to provide a device of this character which is adapted to eliminate back pressure in the exhaust lines of the engine.

A further object of this invention is to provide a device of this kind which through suction formed in the device is adapted to cool the exhaust side of the engine.

A further object of this invention is to provide, in a manner as hereinafter set forth a means whereby through the suction of the exhaust gases from the engine the incoming unburned gases may be entirely used for the production of power so that the power of the engine is thereby increased.

This invention is a division of my co-pending application, Serial No. 217,764 filed July 6, 1938.

To the above ends essentially and to others which may hereinafter appear, the invention consists of the novel construction, combination and arrangement of parts as will be more specifically described and illustrated in the accompanying drawing wherein is shown an embodiment of the invention, but it is to be understood that changes, variations and modifications may be resorted to which fall within the scope of the invention as claimed.

In the drawing:

Figure 1 is a top plan view of the attachment showing the adaptation thereof with respect to an internal combustion engine. The engine is shown in dotted lines.

Figure 2 is a longitudinal sectional view of the attachment.

Figure 3 is a longitudinal sectional view of a modified form of attachment.

Figure 4 is a fragmentary view in side elevation illustrating the whirling or deflecting means for the exhaust gases from the engine, and

Figure 5 is an inner end view of the structure shown by Figure 4.

Referring to the drawing, and first to Figures 1 and 2, the character E designates generally an internal combustion engine which in the present instance is disclosed as a four cylinder engine being provided with four separate exhaust outlets on one side thereof. In order to provide

a suction on the exhaust side of the engine E there is installed with the latter, the attachment in accordance with this invention. The said attachment is in the form of a Venturi structure and is so termed.

The structure includes a series of tandemwise disposed coupled together horizontally disposed open rear housings 15, 25, 32 and 38, of like form, and a set of spaced axially aligned horizontally disposed inner annular members 19, 28, 34, 40 of like form and each of uniform diameter. The housings 15, 25, 32 and 38 include front end walls 18, 23, 31, 37 respectively; annular front end parts 17, 21, 27a, 27b respectively of uniform diameter and of less diameter than the said front parts; annular tapered intermediate parts 15a, 15b, 15c and 15d respectively which gradually decrease in diameter from the front parts to said rear parts; and spaced exhaust gases conductors leading from the exhausts of the cylinders of the engines to the outer housings, and each of said conductors is shown by way of example as a tube. The housings 15, 25, 32, 38 have connected thereto the exhaust conducting tubes 16, 26, 33, 39 respectively opening into the inner sides of the front end parts 17, 21, 27a, 27b respectively. The front end walls 18, 24, 31, 37 are formed with openings 18a, 24a, 31a and 37a respectively having their axes aligning with the axes of the rear parts of said housings.

The members 19, 28, 34 and 40 are secured intermediate their ends to the walls of the openings 18a, 24a, 31a, 37a respectively. The member 19 has a portion extending rearwardly from wall 18 and a portion extending forwardly from such wall; the member 28 has a portion extending rearwardly from wall 24 and a portion extending forwardly from such wall; the member 34 has a portion extending rearwardly from wall 31 and a portion extending forwardly from such wall; and the member 40 has a portion extending rearwardly from wall 37 and a portion extending forwardly from such wall. The forward end of member 19 is provided with a flange 20 for attaching to said member 19 a forced air conducting means 21 leading from the engine E, as more particularly described in my application aforesaid. The member 19 constitutes a forced air intake for the Venturi structure and also a conductor for such air. The members 28, 34 and 40 constitute conductors for a mixture formed of air and exhaust gases. The rear part 42 of housing 38 constitutes an outlet for the mixture aforesaid. The part 42 is flanged, as at 43, for connection to a conducting-off means, not shown. The rearwardly ex-

tending portions of the members 19, 28, 34 and 40 are arranged within and spaced from the inner faces of the intermediate parts of the housings, as well as being spaced forwardly from the rear end parts of the housings. The housings have their intermediate parts of greater length than their front or rear end parts. The rear ends of the annular members 19, 28, 34 and 40 are spaced from the rear ends of and discharge into 10 the tapered intermediate parts of the housings.

Between the rear ends of the forward members of the set of members and the forward ends of the rear members of the set of members, the housings 15, 25 and 32 are formed with mixing 15 chambers indicated at 73, 74, 75 respectively. The housing 38 is formed with a mixing chamber 76.

The forwardly extending portions of the rear members of the set of members coact with the 20 rear end parts of the rear housings 15, 25 and 32 of the series of housings for coupling the housings of the series together in tandemwise relation.

The rear end portions of the outer periphery of the members 19, 28, 34 and 40 are tapered 25 and provided with blades, fins or ribs 22, 29, 35, 41 respectively which coact with the said peripheral portions to form grooves having their bottoms inclining downwardly from their leading ends to their follower ends. The grooves are 30 open at each end and have their rear ends open at the rear ends of the members 19, 28, 34 and 40. The grooves in connection with the blades 22, act to deflect or whirl the exhaust gases after 35 being supplied to the front end parts of the housings. The fins on each member are of like form, of substantially spiral contour arranged thereon in a circumferential row and are disposed substantially lengthwise of the member.

The forward movement of an automobile or 40 an air craft will compress atmospheric air into the intake tube through the funnel directly into the annual member of the forward housing with respect to the structure shown by Figure 3, and into the vacuum chambers about the engine, 45 with respect to the structure shown by Figure 2, building up a pressure therein which leads into the means 21. The said means 21 open directly into the forward end of member 19. The compressed atmospheric air acts as a motive fluid for 50 producing suction in the exhaust lines from the engine cylinders.

The hot gases discharging from the series of cylinders are conducted to the housings of the device and flowing through the grooves on the 55 tapered periphery of the annular members, direct the gases toward a center, forming a pocket of hot gases rotating in a vortex creating pocket of lessened pressure to the rear of the center which fills up from the rear as a void will fill up, 60 manifesting a suction in the annular member. This suction in the annular members results whether the vehicle is at rest or in motion and is not dependent on the pressure of the atmospheric air built up through the air intake or funnel. Inasmuch as the spiral tapered grooves on 65 the series of annular members, each operate separately and independently causing suction through the length of the annual members, which are coaxially arranged, it is obvious that any opening into the series of annular members coaxially arranged and joined into each other will be operated upon by the suction produced in the annular members and as some of the exhaust valves leading from the cylinders are open when 70 some are closed there will always be gases rotat-

ing through the grooves of its particular nozzle head, causing a suction in the annular members coaxially arranged so that when the exhaust valve reopens the suction will pull on the cylinder thereby more rapidly scavenging the gas therein which, in turn, will create suction in the annular members after rotating to the center. If but only a single injector is used the scavenging would be limited to the degree that the exhaust gases exhaust faster by reason of the rotation of the gases, but in series, the operation of the gases through the injector from the exhaust lines whose valves are open gives continuity to the suction created in the annular members coaxially arranged so that the pulling effect is felt 15 on any port opening into it.

In addition, the fact that the atmospheric air that rushes into the pocket formed by the hot exhaust gases in the vortex described results in a rapid expansion and accelerating of the 20 center forwardly or increased velocity of the mixture.

The fact that the forced air operating through the vacuum chambers about the cylinders and into the air pipe or directly through the funnel 25 into the air tubes adds motive fluid which, when the vehicle is in motion, augments the force of the suction upon the exhaust gases. The combined effect of the suction produced by the rotation of the gases and the suction induced by 30 the motive fluid of the air will effectively scavenge the gases of the moving vehicle.

It will be apparent that even if the suction in the air tubes only overcomes atmospheric pressure in the exhaust line at the end of the discharge pipe or tail pipe, that the suction on the cylinders induced by the motive fluid of forced air will be increased and made more effective on the cylinders to that extent, otherwise, the gain against the cylinders would be lessened by 40 the resistance of the atmospheric pressure at the end of the discharge pipe into the atmosphere.

Although the attachment, as shown, is illustrated in connection with an engine of the four cylinder type, it is to be understood that it is 45 for use in connection with any engine having any desired number of cylinders.

In Figure 3, I have shown a slightly modified form of this suction device wherein I have provided a substantially frustro-conical body 15^a 50 which has a pipe or nipple 16^a secured thereto having a flange 44 at its outer end for attachment to the exhaust port of the engine. The body 15^a is provided with a substantially cylindrical base portion 17^a and an end wall 18^a closes 55 the outer end of the cylindrical portion 17^a. An air tube 19^b is threaded through the end wall 18^a and projects slightly beyond the outer side of the wall 18^a. A funnel shaped intake member 45 having an enlarged inner end portion 46 is 60 threaded onto the projecting end of the air tube 19^b.

This funnel member 45 constitutes an intake so that this member may be directed forwardly of the engine so that the forward movement of the vehicle will tend to force the air inwardly through 65 the intake member 45.

In order to provide a means whereby the quantity of air entering the air tube 19^b may be properly regulated, I have provided a butterfly 70 valve 47 which is mounted on a shaft 48. The valve 47 is disposed inwardly of the forward end of the funnel 45 and may be controlled by means of a handle or operating member 49. The inner end of the air tube 19^b is provided with spirally 75

arranged fins 22^b similar to the fins 22, and the inner end of the body 15^a is provided with a cylindrical portion 50 in which an intermediate or inner air tube 51 is threaded. An air tube 51 extends through an end wall 52 of an intermediate member 53. The reduced or inner end of the member 53 may be secured as by welding or the like to an end wall 54 of a second inner or intermediate member 55. The intermediate member 53 is provided with a pipe 56 having a flange 57 for attachment to an exhaust port and the exhaust gases discharging from the intermediate member 53 are adapted to pass spirally arranged fins or blades 58 provided on the inner end of the air tube 51.

An air tube 59 is threaded into the end wall 54 of the body 55 and this air tube 59 is provided with spirally arranged fins or blades 60 on the inner end thereof. A tube or pipe 61 communicates with the body 55 and is provided with a flange 62 for attachment to an exhaust port. The forward end of the body 55 is provided with a cylindrical portion 63 forming a mixing chamber 64, and an air tube 65 is threaded through an end wall 66 of an outer body 67. The body 67 is similar to the body 15^a being provided with a pipe 68 having a flange 69 for attachment to an exhaust port.

The small or apex end of the body 67 is provided with a flange 70 so as to permit the attachment of a carry-off means or pipe to a suitable device such as a low pressure turbine, a muffler or other similar device. The space between the inner end of the tube 19^b and the apex of the body 15^a forms a mixing chamber 71, and the space between the inner end of the tube 51 and the end wall 54 provides a mixing chamber 72.

What I claim is:

An attachment for internal combustion engines of automotive vehicles, said attachment including a series of tandemwise arranged, horizontally disposed open rear housings having front end parts, rear end parts, tapered intermediate parts, front end walls for said front end parts and mix-

ing chambers in the rear of said intermediate parts, a set of axially aligned spaced horizontally disposed tandemwise arranged annular members opening at their rear ends into said chambers, the foremost member of said set being secured 5 intermediate its ends to and extending through the front wall of the foremost housing, the other members of said set being secured at their forward ends to the rear end parts of and extending rearwardly through the front end walls of the 10 others of the said housing, the said annular members being of uniform inner diameter and having their inner portions spaced from the said front, intermediate and rear parts, the foremost member of said set constituting a combined intake and 15 conductor for a suction creating motive fluid in the form of forced atmospheric air created on the travel of the vehicle, the others of the said members constituting conductors, means communicating with the atmosphere for conducting forced 20 atmospheric air to said foremost member, means connected to the forward end part of each housing for supplying exhaust gases therein forwardly of the intermediate part and rearwardly of the front wall of such housing, each of said members 25 having the rear terminal portion of its outer periphery tapered, each tapered portion being provided with a circumferentially arranged row of spaced blades substantially of spiral form disposed substantially lengthwise of the said periphery, said rows of blades coacting with said tapered portions to provide groups of substantially spiral grooves opening at their leading and follower ends and having inclined bottoms, said grooves, blades and tapered portions providing 30 for the rotation of the gases supplied to the housings to create a suction on the incoming gases whereby the combined effect of the suction produced by the rotation of the gases and the suction induced by the motive fluid will effectively 35 scavenge the exhaust gases from the moving vehicle, and the open rear end of the rearmost housing constituting an outlet for the attachment.

URBAN SAUER.
